UNITED STATES PATENT OFFICE.

TAKEJIRO YAMAMOTO, OF NISHINARI-GUN, OSAKA, JAPAN.

INTERLOCKING SPLICE FOR THREADS OF TWO STRANDS.

Application filed May 3, 1922. Serial No. 558,233.

To all whom it may concern:

Be it known that I, TAKEJIRO YAMAMOTO, subject of the Emperor of Japan, residing at 29 Hori, Kamitsu-Mura, Nishinari-gun, 5 Osaka, Japan, have invented certain new and useful Improvements in Interlocking Splices for Threads of Two Strands, of which the following is a specification.

My invention relates to an improvement 10 in an interlocking splice for threads of two strands, and is especially adapted to be used in uniting the threads to form a net. In the splice which constitutes my invention, each strand of one thread crosses each strand of 15 the other thread at two points so that the strands of both threads form four crossings.

The general object of the invention is 20 the production of a splice which will not be easily loosened or displaced, thus resulting in a strong and durable net.

The invention will be best understood from the following description, taken in connection with the accompanying drawing, in which:—

25 Fig. 1 shows a pair of threads interlocked according to the invention, with the strands separated in order to illustrate their relation.

Fig. 2 is a view showing the splice after 30 the threads have been drawn taut.

Referring more specifically to the drawing, *a* designates a thread made of two strands 1 and 2, twisted together in the usual manner, and *b* designates another 35 thread composed of two strands 3 and 4.

The two threads *a* and *b* are interlocked to form a splice as shown in Fig. 2.

In forming my improved splice, each 40 thread *a* and *b* is twisted for the desired length, and the strand 1, of the thread *a* is crossed with the strand 3 of the thread *b*;

next, the strand 2 of the thread *a* is crossed with the strand 4 of thread *b*; next, the strand 1 of thread *a* is crossed again with the strand 3 of thread *b*; and finally, the strand 45 2 of thread *a* is crossed with the strand 4 of thread *b*.

Thus, each strand of one thread intersects at two points with each strand of the other thread, so that the strands of both threads 50 55 form four crossings at the points A, B, C and D, respectively.

After the splice is thus completed, each thread beyond the splice is again twisted for the proper distance, where it is again 55 spliced with another thread.

In nets heretofore constructed, where the juncture of the threads has been made by a single braid knot, the same becomes easily 60 loosened, and after the net has been in use for some time, the knot becomes displaced so that the size and shape of the meshes become altered. This invention, therefore, is designed to correct this deficiency. In a net 65 constructed like the present invention, the strands cross each other at four points in each splice, so that the union is very strong and the strands are securely held so that they cannot be displaced even after long use.

What I claim is:—

70 An interlocking device for threads of two strands, in which each strand of one thread crosses each strand of the other thread at two points, whereby the strands of both threads form four crossings, substantially as 75 set forth.

In testimony whereof I affix my signature in presence of two witnesses.

TAKEJIRO YAMAMOTO.
